UNITED STATES PATENT OFFICE.

MOSES DUBINSKY, OF PHILADELPHIA, PENNSYLVANIA.

PATTERN-FORMER.

No. 926,322.

Specification of Letters Patent.

Patented June 29, 1909.

Application filed September 4, 1908. Serial No. 451,646.

To all whom it may concern:

Be it known that I, MOSES DUBINSKY, a citizen of the United States, residing at 2502 North Seventeenth street, in the city and county of Philadelphia and State of Pennsylvania, have invented a new and useful Improvement in Pattern-Formers, of which the following is a specification.

My invention relates to improvements in adjustable and graduated pattern formers, and my object is to provide a new and improved device of this character, adapted more particularly to laying out patterns for ladies' fur coats or jackets, which shall be readily and accurately adjustable to all variations in form and proportion, both for stock and for measure work.

My improved pattern former consists of a series of principal frames and of auxiliary forms to be used in connection therewith, the members or parts whereof are adjustable relatively to each other and are furnished with scales or graduations to facilitate any desired adjustment to body measurements. The members are connected by pivots and studs and are clamped in position by thumb-screws when adjustment of the frame or form is complete.

In the accompanying drawings Figure 1, Sheet 1, shows the pattern former for the front of the coat; Fig. 2, Sheet 2, that for the under-arm piece; Fig. 3, Sheet 2, that for the side body; Fig. 4, Sheet 2, that for the back of the body; Figs. 5 and 6, Sheet 3, show pattern formers for semi-fittings, employed in substitution for the side-body piece shown in Fig. 3; Figs. 7 and 8, Sheet 4, those for the outer and under sleeve sections; Figs. 9 and 10, Sheet 5, those for single and double darts respectively, for tight-fitting; Fig. 11, Sheet 6, that for a revers for either furs or cloaks; Fig. 12, Sheet 6, that for a notch collar for fur coats; Figs. 13 and 14, Sheet 5, those for the outer and inner sections of a storm-collar; Fig. 15, Sheet 3, that for a shawl collar; Figs. 16 and 17, Sheet 6, those respectively for front and back loose coat attachments; Fig. 18, Sheet 6, that for a notch collar for cloaks; Fig. 19, Sheet 4, that for a neck attachment for waists; Fig. 20, Sheet 3, that for a choker for waists, and Fig. 21, Sheet 4, that for the shoulder back attachment.

The members of my pattern former may be constructed from any suitable material, preferably sheet metal, of such thickness or stiffness as to properly preserve the shape of

the frame or form when clamped, and to secure the requisite adjustability of the several members.

Throughout the specification those members which are integral I shall designate as rigidly connected; those members which are pivotally connected I shall designate as pivoted. Those members which are slotted and slidably connected by studs and thumb-screws, I shall designate as adjustably connected.

In the accompanying drawings the secondary numerals accompanying the numerals of reference indicate integral parts of the same number as 1, 1¹, 1², 1³.

In Fig. 1, which shows my pattern former for the front of the coat, the member 1 is formed with the graduated offset 1¹ and the parallel arms 1² and 1³, the former being graduated. The members 2 and 3 are pivoted upon the member 1 and adjustably secured thereto.

The members 4 and 5, substantially identical in form, are furnished with the arms 4¹ and 5¹ between which passes the offset 1¹, the member 4 being graduated. The members 1, 2 and 3 are also inclosed between the members 4 and 5 which are adjustably connected to the members 1, 2 and 3. The member 6 is formed with a slotted and graduated body and an arm 6¹, the latter being adjustably secured to the arm 1². The member 7 is adjustably secured upon the member 6. The graduated member 8 is pivoted upon the member 7. The member 9 is adjustably secured to the member 8 and to the graduated member 10, which is pivoted to the ends of members 4 and 5. The members 11 and 12 are graduated and adjustably secured, by a stud common to both members, to the member 6. The arm 12¹ of the member 12 is further secured by a thumb-screw in the slot of the member 6. The member 13 is adjustably secured to the parallel arms 1³ and 6¹. The arms 13¹, 13² and 13³ of the member 13 are slotted, the arms 13¹ and 13² being graduated; and to the arms 13¹ and 13² is adjustably secured the member 14 by its arms 14¹ and 14², the upper end of the member 14 being similarly secured to the graduated member 11.

The upper end of the member 15 is pivoted upon member 14, the pivot being formed with a stud which is mounted in the slot of member 11, so that while member 15 is pivoted upon member 14, both members are ad-

justably mounted as a unit upon member 11. The graduated arm 15¹ of the member 15 has adjustable connection with one end of the member 16, the other end of the latter being 5 adjustably secured to the arm 13².

The member 17 is formed with the graduated and doubly slotted arm 17² and the projection 17¹ and is adjustably secured to the graduated member 12. The member 18 is 10 formed with the graduated arms 18¹ and 18² which are adjustably connected to the member 17 by the members 19 and 20. The member 21 is pivoted through members 19 and 17, the members 21, 19 and 17 being adjustably secured as a unit upon the member 12. The arm 21¹ of the member 21 is adjustably secured to the arm 17². The member 22, provided with the graduated arm 22¹, is pivoted at its upper end through the member 18 so that the members 18 and 22 are adjustably mounted as a unit in the coincident slots of graduated members 23 and 24, the member 23 being adjustably secured to member 24. The arm 22¹ and the lower end of member 18 are adjustably secured to the arm 17² by the connecting member 25. A further graduated member 26 adjustably connects the two lower halves, so to speak, of the frame shown in Fig. 1. Reverting to the right-hand upper portion of Fig. 1, the member 27 having the arm 27¹ is adjustably secured to the member 7, while the arm 27² makes an adjustable connection with the member 24.

Having thus set forth the component members of that portion of my pattern former shown in Fig. 1, I will describe its mode of adjustment for laying out the pattern.

My invention may be employed either in 40 the preparation of patterns for ready-made garments or stock work, or for measure or custom work. I will therefore first describe the adjustment of my pattern former for the laying out of stock patterns.

45 In laying out stock patterns for ready-made garments, it is well-known that the bust measure is taken as a unit which determines all succeeding measurements. I accordingly proceed as follows: For a bust measure of, say 36, the member 7 is adjusted upon the member 6 until the left hand edge of member 7 coincides with the graduation 36 on the member 6, when 6 and 7 are clamped. The members 13¹ 14¹, 19 and 18¹ 50 represent the waist line. Accordingly the members 14¹ and 19 are respectively set at the graduation 36 on the members 13¹ and 18¹. In like manner the left-hand end of the member 12¹ is set at 36 on the lowermost series of graduations on member 6. The members 13², 14², 17¹, 20 and 18² represent the line of the hips. Accordingly an adjustment to 36 is made of members 14² and 20 upon the graduated members 13² and 18². 60 65 Reverting to the upper portion of Fig. 1,

the offset 1¹ has two distinct series of graduations. Those extending lengthwise of the member beginning at the lower side, indicate respectively the adjustment for tight-fitting, three-quarter tight, half-loose and loose. The graduations at right angles to those above described are numbered from left to right from 32 to 46. The arm 4¹ of the member 4 is so notched as to be capable of adjustment to both series of graduations. 70 The left-hand edge of the arm 4¹ being set at 36, the notch is then adjusted to the longitudinal graduations according to the desired size or style, tight-fitting, three-quarter tight, etc., as above described. This adjustment correspondingly shifts the position of the shoulder point at the upper end of member 4 and also regulates the shoulder width. A feature to be noted in connection with this and the succeeding frames and auxiliary forms is that at the necessary points of sliding connection or adjustment I have graduated the members from 32 to 46, and that in consequence, for trade or stock work it is only necessary for the operator to determine the desired bust measure, as, for example, 36, and thereupon adjust and secure the several members of the pattern former to graduation 36. The pattern may then be marked out without further measurement 80 or calculation on the part of the operator. 85

Having described the adjustment of so much of my pattern form as is embodied in Fig. 1, in laying out patterns for stock work, I will now set forth its mode of adjustment 90 for measure work.

I have prepared a table for use in connection with my improved pattern former, wherein under each bust measure from 32 to 46 I have tabulated the accompanying round 105 and length measures. For example, for bust measure 32 the waist measure is 21 $\frac{1}{2}$ and hips 38. For bust measure 34 the waist measure is 22 $\frac{1}{2}$ and hips 40, and so under each bust measure every requisite round and length 110 measure is tabulated. In measure work the bust measure is taken and the adjustment made upon Fig. 1, as hereinbefore described in stock work. The waist measure is then taken, which we will suppose to be 22 $\frac{1}{2}$. 115 This will be found under the table of bust measure 34. The members of the frame are therefore adjusted for the waist measure at the graduation 34. The hip measure, we will assume, proves to be 38, which is found under the table of bust measure 32 and the adjustment for the waist measure is therefore made at the graduation 32 on those members of the pattern former which represent the waist measure. This process is repeated for 120 each measurement as taken from the person to be fitted. Thus I avoid the necessity for a double set of graduations upon each number of the pattern former and am enabled by a single set of graduations upon the members 125 130

to lay out patterns as well for measure work as for stock work.

Continuing now my description of the adjustment of Fig. 1 for measure work, the member 26 affords the necessary adjustment for flat or high stomach, the two lower sections or halves, so to speak, of Fig. 1 being separated or approximated thereby in accordance with the graduations on members 10 15¹ and 17², each line on said graduations representing a size. In like manner the member 22 is adjustable to the requisite hip measure. To obtain the requisite length measures, back and front, the lower portion 15 of the frame in Fig. 1 is vertically adjustable upon the members 1³, 6⁴, 11, 12 and 23. An independent adjustment for the under-arm measure is obtainable through the members 24, 23 and 18. The requisite adjustment for 20 a long or short front is obtainable through adjustment of member 1 with its curved offset 1¹. The member 60, Fig. 1, constitutes the pattern former for a revers or lapel, where a pattern for one is required in connection with the coat front pattern.

In Fig. 2, Sheet 2, which shows the pattern former for the under-arm piece, the graduated member 28 is formed with the graduated arm 28¹ to which is adjustably secured the 30 arm 29¹ of the graduated member 29, the members 28 and 29 being further adjustably connected by the member 30, the arm 31¹ of the member 31 being adjustably secured to the member 32, and both members being adjustably mounted upon the slotted member 35. The members 32 and 33 are laterally 40 adjustable by means of the graduated arms 32¹, 32², 33¹ and 32³, and both the member 33 and the arm 32¹ are adjustably secured to the member 28.

The method of adjustment of Fig. 2 is as follows: For stock work the members are adjusted to the proper graduations in accordance with the system hereinabove described 45 in connection with Fig. 1. For measure work, the requisite length under arm in particular cases is obtained by adjusting the member 30 vertically upon the members 28 and 29 and by similarly adjusting the members 31, 32 and 33 upon the members 28 and 29. The requisite width for the hips is obtained by lateral adjustment of the member 32 with its arm 32² upon the member 33. A further adjustment for hip measure is obtained through adjustment of the member 31 with its arm 31¹ upon the member 32³.

In Fig. 3, Sheet 2, which shows the pattern former for the side-gore, the members 34, 35 and 36 are superimposed upon each other in 60 the order named, the member 34 being graduated at its lower end. The lower end of the member 35 is pivoted upon the member 34, its upper end being transversely slotted. The lower end of member 36 is likewise transversely slotted and both members

36 and 35 are adjustably secured at this point to the member 34. The member 36 is longitudinally slotted at its upper end and is provided with a series of perforations bordering said slot. The slotted and graduated member 37 is furnished with a graduated arm 37¹ to which is adjustably secured the enlargement 34¹ of the member 34. The member 38 is adjustably secured to the lower portion of the member 34 and is furnished with 70 the graduated arms 38¹ and 38² and the graduated arm 38³. The member 39 with its arm 39¹ is adjustably secured to the arm 38¹ and to the member 37, to the arm 38² and to the arm 38³. The upper end of the member 40 is pivoted upon the member 38, both members being adjustably mounted as a unit upon the member 34, and the arm 40¹ of the member 40 is adjustably secured upon member 38. The upper ends of members 34 and 36 on the one hand and of member 37 on the other are adjustably connected by the member 41.

Having described the component parts of the frame shown in Fig. 3 I will now set forth 90 the mode of adjustment thereof.

For stock work the adjustment of members is made according to the principle hereinbefore described. For measure work the requisite length of the side-gore is obtained by vertical adjustment of the members 41, 38 and 39 upon the members 34 and 37, as hereinabove described in connection with Fig. 2. The member 40 is designed to secure an optional adjustment for a pattern 100 with or without plait. The enlargement 34¹ is adjustable upon the graduated member 37¹ to afford the requisite bust measure adjustment. The members 35 and 36 are laterally 105 adjustable upon the enlargement 34¹ for flat back, round shoulder, or hump, the requisite graduations for such adjustment being marked upon the enlargement 34¹ of the member 34.

In Fig. 4, Sheet 2, which shows the pattern 110 former for the back part of the garment, the graduated member 42 is formed with the arm 42¹. The member 43 is formed with the arm 43¹ and the rectangular enlargement 43² which is adjustably secured to the member 115 42. The member 44 lies directly behind the upper half of member 43 and has both vertical and lateral adjustment relatively thereto. One end of the member 45 is adjustably secured between the end of the member 44 120 and the arm 43¹, the other end of the member 45 being adjustably secured to the arm 42¹ of the member 42. The member 45¹ is pivoted at its upper end to the member 42 and is overlaid by the member 46 which is adjustably secured to the member 45¹ and is furnished with the notched and perforated head 46¹. The member 47 is formed with the arm 47¹, the graduated arm 47² and the graduated arm 47³. The upper end of the member 48 is 130

pivoted in the member 47, while the lower end is furnished with the arm 48¹ which is adjustably secured to the arm 47² of the member 47. The member 49 is adjustably secured to the arm 47¹ and member 45⁴, to the graduated arm 47² and to the arm 47³.

The mode of adjustment of Fig. 4 is as follows: For stock work the adjustment of members is according to the system hereinbefore described. For measure work the requisite length is obtained by adjusting member 47 upon member 43. By lateral adjustment of the members 48 and 49 the pattern for the back piece may be laid out either with or without plaits or slits. Width of hips is obtained by adjusting the arm 47², and width of back by adjustment of the member 43² upon the member 42, a corresponding adjustment of the member 45 being effected in connection therewith. Adjustment for narrow chest and wide back is effected through the member 46, 46¹. The perforations *a*, *b*, *c* and *d* in the member 36 of Fig. 3 correspond to the equal number of perforations *a*¹, *b*¹, *c*¹ and *d*¹ in member 46¹ of Fig. 4, whereby the requisite adjustments for size or style may be effected, the perforations in member 36 being fitted to the corresponding perforations in member 46¹.

In Fig. 5, Sheet 3, which shows the pattern former for semi-fittings, the member 50 is provided with the graduated arms 50¹ and 50² and the arm 50³. The member 51 is adjustably secured to the arms 50¹ and 50² and is pivoted to the connecting piece 51^a which is adjustably secured to the arm 50³ of the member 50. The members 52, 53 and 54 are adjustably secured to each other, the last member being adjustably secured between the member 51 and the arm 50¹ of the member 50. The member 52 is graduated and is furnished at its upper end with the rows of perforations *e*, *f* and *g*. In Fig. 6, Sheet 3, which also shows a pattern former for semi-fittings, the member 55 is provided at its lower end with the arm 55¹. The member 56 is provided with the graduated arms 56¹ and 56² and the arm 56³. The members 57, 58 and 59 are adjustably secured to each other, the last member being adjustably secured to the member 55. The member 57 is furnished at its upper end with the rows of perforations *e*¹, *f*¹ and *g*¹.

Having set forth the component members of Figs. 5 and 6 constituting the pattern formers for semi-fittings I will now describe the manner in which said pattern-formers are used to increase the widths of the patterns formed from Figs. 2 and 4. The pattern former for the under-arm piece shown in Fig. 2, being adjusted in accordance with measurements taken from the person to be fitted, its several members are clamped, the pattern former is laid down upon a sheet of paper and the outline of the under-arm piece

is marked out upon the sheet, following the upper edge of member 30, the outer edges of members 28 and 33, the lower edges of members 33¹, 32³ and 31¹ and the outer edges of members 31 and 29. If, now, the body measurements require that the widths of the pattern thus laid out upon the sheet be increased, the pattern former shown in Fig. 5 is laid down upon the pattern already marked out from Fig. 2, the members 52, 53, 54 and 51 of Fig. 5, being so adjusted that their inner or left hand edges fit to the right hand side line of the pattern formed by Fig. 2. The members 52, 53 and 54, Fig. 5 are, at the same time adjusted longitudinally so that the curved upper edge of member 52 forms a continuation of the curve marked upon the sheet by the upper edge of member 30, Fig. 2, and so that the lower end of member 51, Fig. 5, with the lower edges of members 51^a and 50³ are coincident with the line laid out upon the sheet by the member 33¹, 32³ and 31¹, Fig. 2. The member 50, Fig. 5 is then drawn out laterally, keeping the point 50⁴ upon the left-hand side line already laid out upon the sheet, until the distance from the outer edge of member 51, Fig. 5 to the outer edge of member 50 represents the actual desired width of the under-arm piece in the garment. These adjustments having been effected, the members of Fig. 5 are clamped and an increase in the widths of the under-arm piece as originally laid out from Fig. 2 is obtained by following with a pencil the outer or left hand edge of member 50, Fig. 5 and the outer or right hand edges of members 52, 53, 54 and 51. Any one of the rows of perforations *e*, *f* and *g* in the upper end of member 52, Fig. 5 may be used to continue the curved top of the under-arm pattern, where the body measurements so require, instead of using the upper edge itself of member 52 as above described. The pattern former for semi-fittings shown in Fig. 6 is used in like manner to increase, when necessary, the widths of the pattern for the back piece formed from Fig. 4. The latter, being adjusted and clamped, is laid down upon the sheet and the pattern is marked out following the outer edges of members 42¹, 45, 44, 43, 47, 48², 48¹, 47³, 49¹, 45^a, 46 and 46¹. Upon the pattern thus formed is laid the pattern former shown in Fig. 6; the right hand edges of members 57, 58, 59 and 55, Fig. 6 being adjusted to coincidence with the left-hand side line of the pattern formed from Fig. 4. The member 56, Fig. 6, is drawn out laterally, keeping the point 56⁴ upon the right hand side line of the original pattern. The upper curved end of member 57, Fig. 6 is adjusted to form a downward continuation of the left-hand outer edges of member 46¹, Fig. 4, or, if required, any one of the successive curved rows of perforations *e*¹, *f*¹ or *g*¹, in member 57, Fig. 4, may be adjusted to 130

form such continuation. In Figs. 2 and 5 the members 32¹ and 50¹ represent the waist line and must be kept coincident in the above described super-imposition. The same is true of members 32² and 50² which represent the line of the hips.

Not only do the pattern formers for semi-fittings shown in Figs. 5 and 6 increase the widths of the patterns laid by Figs. 2 and 4, but it should also be observed that the former modify the character of the curves formed by the latter. When the left-hand edges of members 51, 54, 53, and 52 of Fig. 5 are adjusted to the line laid out by the right-hand edges of members 32 and 29 of Fig. 2 and a new side-line for the pattern is formed by following the right-hand edges of members 51, 54, 53 and 52, Fig. 5, this new side-line is by no means parallel with or a mere extension of the line formed by members 32 and 29 of Fig. 2. In other words, there is obtained by the use of said semi-fitting pattern formers not merely an increase in the widths of the pattern, but a modification of its side-line curve as well. And the same is true of the function of the semi-fitting pattern former shown in Fig. 6 as employed in connection with the pattern laid out by Fig. 4.

In Fig. 7, Sheet 4, which shows the pattern former for the upper sleeve, the member 61 is graduated and is furnished with the graduated arm 61¹. The member 62 is formed with the arm 62¹ whereby it is adjustably connected to the arm 61¹. The graduated member 63 is adjustably connected to the member 62 and is pivoted upon the member 64 which, in turn, is adjustably connected to the member 65. The member 66 is pivoted upon the member 65 and adjustably connected to the member 61. The lower end of the member 67 is adjustably connected to the member 62, and its upper end is pivoted upon the member 68 which is adjustably connected to the member 69. The members 70 and 71 are adjustably connected to each other and to the members 61 and 69 at one end and to the members 62 and 67 at the other. Adjustments for width at the top of the sleeve are made by means of the members 70 and 71, the member 68 sliding correspondingly upon the member 69; and for the lower width by adjustment of member 62¹ upon member 61¹ and of member 64 upon member 65. Adjustments for length are obtained by lengthening members 61 and 62 upon members 69 and 67 and by similarly lengthening members 63 and 66 upon members 62 and 61.

In Fig. 8, Sheet 4, which shows the pattern former for the under sleeve, the member 72 is formed with the graduated arms 72¹ and 72². The member 73 is formed with the arm 73¹ whereby it is adjustably connected to the arm 72², and the arm 73² whereby it is adjustably connected to the arm 72¹. To the

lower end of the member 73 is adjustably connected the graduated member 74. The member 75 is pivoted at one end to the member 76 which is adjustably connected to the member 72. The other end of the member 75 is adjustably connected to the member 74. The member 77 is adjustably connected to the member 72. The member 78 is adjustably connected to the member 73. The members 79 and 80 are pivoted respectively to the members 77 and 78 and are adjustably connected to each other. Adjustments for width and length are obtained as in Fig. 7, by adjustments which are sufficiently obvious in view of the foregoing explanations.

In Fig. 9, Sheet 5, the members 81 and 82 are adjustably connected by the members 83, 83¹, 83² and by the member 84. The horizontal graduated member 85 carries the ends of the members 86 and 87, the latter being adjustably mounted thereon by its arm 87¹, the graduated lower ends of the members 86 and 87 being adjustably secured between the upper ends of the members 81 and 82 and the arm 83¹ of the member 83.

In Fig. 10, Sheet 5, the members 88 and 89, 90 and 91, 92 and 93, and 94 and 95 are adjustably connected in pairs, the lower portions of the members 89 and 95 being graduated and the lower portions of the members 88, 91, 93 and 95 being slotted. These eight members are adjustably mounted upon the connecting member 96. The lower ends of the members 88 and 90 and of the members 92 and 94 are adjustably connected respectively by the members 97 and 98. The upper ends of the members 89, 91, 93 and 95 are adjustably connected to the graduated member 99.

Figs. 9 and 10 constitute the pattern formers for laying out the darts—a single dart in Fig. 9 for cloaks or furs, or double darts in Fig. 10 for cloaks or waists. The mode of adjustment is as follows: After the pattern has been laid out by Fig. 1, Sheet 1, Fig. 9 is laid down upon the pattern thus marked, the lower edge of member 85 being made coincident with the line $x-x$ indicated upon members 1¹ and 6¹ in Fig. 1, and the left-hand end of member 85 being made coincident with the left-hand edge of member 1, 1¹. The member 87¹ is then adjusted to the same graduation on member 85 as that at which the member 12¹ stands on the member 6, Fig. 1. Adjustment for width of dart is made upon the arms 83¹, 83² and 84; and for length, by vertical adjustment of members 86 and 81 and 87 and 82 respectively. In Fig. 10 a similar adjustment is made to the pattern marked out by Fig. 1. The left-hand edge of member 99 is made coincident with the left-hand edge of member 1¹, but the lateral adjustment is made by bringing the slot 99¹, Fig. 10, to coincidence with the line $x-x$ Fig. 1. The arm 89¹ is adjusted to the gradu-

tion on member 99 corresponding to that of arm 12¹ on member 6, Fig. 1; the arm 95¹ being also adjusted to the corresponding graduation. The width of the double darts is secured by lateral adjustment of the vertical members of Fig. 10 upon the member 96, the desired length being obtained by adjusting members 88, 90, 92 and 94 upon members 89, 91, 93 and 95.

Fig. 11, Sheet 6, shows the pattern former for laying out revers in men's shape for furs or cloaks. The member 100 is formed with the head 100¹ and arm 100². To the head is adjustably secured the graduated member 101, the head 100¹ and arm 100² being connected by the member 102 adjustably secured thereto. This pattern former is employed in connection with Fig. 1, as follows: The right-hand edge of member 100, Fig. 11, is made to coincide with the right-hand edge of the main body of the member 1, Fig. 1, and the member 101, Fig. 11, is fitted over member 4, Fig. 1, the extreme ends of the members being made coincident in laying out patterns for furs, and the end of member 4, Fig. 1, and the graduation y—y on member 101, Fig. 11, being made coincident for cloaks. The member 100 is adjusted to the graduation on member 101 corresponding to the adjustment of Fig. 1. The desired width of revers is secured by lateral adjustment of member 102 at its upper and lower ends.

Fig. 12, Sheet 6, shows the pattern former for a notch collar for furs (men's shape). The member 103 is formed with the arm 103¹ to which is adjustably secured the graduated arm 104¹ of the member 104. One end of the members 105 and 106 is pivoted to the member 103, and the members 105 and 106 are adjustably connected to the members 107 and 108 which are pivoted to the member 104. This frame is longitudinally adjustable according to the graduations on the arm 104¹.

Figs. 13 and 14, Sheet 5, show the pattern formers for the top and under pieces for storm collar. In Fig. 13 the member 109 is formed with the lateral arms 109¹, 109² and 109³ on one side, and 109⁴, 109⁵ and 109⁶ on the other. To the arms 109¹, 109² and 109³ is adjustably secured the member 110. To the arms 109⁵ and 109⁶ is adjustably secured the member 111. The member 112 is pivoted to the member 111 and slidably secured to the arm 109⁴.

In Fig. 14, Sheet 5, the member 113 is formed with the lateral arms 113¹, 113² and 113³ on one side and 113⁴, 113⁵ and 113⁶ on the other. To the arms 113¹, 113² and 113³ is adjustably secured the member 114. To the arms 113⁵ and 113⁶ is adjustably secured the member 115. The member 116 is pivoted upon the member 115 and adjustably secured to the arm 113⁴.

Fig. 15, Sheet 3, shows the pattern former

for the underpiece for a shawl collar. To one side of the member 117 is adjustably secured the member 118, and to the other member 121, the members 118 and 121 being extensible laterally from the member 117 upon the graduated arms 117¹ and 117². A further adjustable connection between members 117 and 118 is furnished by the members 119 and 120 which are respectively pivoted to the top and bottom of member 117 and are movably studded to the arms of member 118. In like manner the member 121 is adjustably secured to the other side of member 117, by the member 122 which adjustably joins the top of member 121 to the arm 117² of member 117. The member 123 adjustably connects the lower end of member 121 to the arm 117⁴ of member 117.

Fig. 16, Sheet 6, shows the pattern former for front attachment for entirely loose coat. The member 124 is furnished with the graduated arm 124¹ and is adjustably secured to the graduated member 125. This pattern former is laid to members 22, 23 and 24, Fig. 1, the top of member 125 coinciding with the top of member 24, and the lower end of member 124 coinciding with the lower end of member 22. Member 124¹ represents the waist line, and must be coincident with members 19 and 18¹, Fig. 1.

Fig. 17, Sheet 6, shows the pattern former for back attachment for entirely loose coat. The member 126 is furnished with the graduated arm 126¹ and is adjustably secured to the graduated member 127. This pattern former is adjusted to the left-hand edge of Fig. 2 in like manner as above described in the case of Figs. 17 and 1.

Fig. 18, Sheet 6, shows the pattern former for a notch collar for cloaks. The members 128 and 129 are laterally extensible upon each other, the degree of adjustment being determined by the graduated arm 129¹, which is adjustably secured to the arm 128¹ of the member 128. The members 130 and 131, and 132 and 133, laterally extensible from each other represent respectively the upper and lower edge of the notch collar.

Fig. 19, Sheet 4, shows the pattern former for a neck attachment for waists. The upper angle of the head 134¹ of the slotted and graduated member 134 is fitted upon the pattern line laid out by the upper meeting edges of members 4 and 10, Fig. 1, the left-hand edge of member 135, Fig. 19 connecting with the curve of the left-hand edge of member 3, Fig. 1.

Fig. 20, Sheet 3, shows the pattern former for a choker for waists, the members 136 and 137 being laterally extensible upon each other as in the case of Fig. 18 by means of the adjustably connected arms 136¹ and 137¹ together with the members 138, 139, 140 and 141, which latter four members, paired in the

order named and likewise adjustably connected, represent the upper and lower edges of the choker.

Fig. 21, Sheet 4, shows the pattern former 5 for the shoulder back attachment. The left-hand edge of member 142 is fitted to the left-hand edge of members 42 and 46¹, Fig. 4, and the upper edge of member 143 to the upper edges of members 45 and 42¹, Fig. 4.

10 What I claim as my invention and desire to secure by Letters Patent is:

1. A coat-front pattern former, consisting of the members 1, 1² and 1³ for laying out the front line, the doubly graduated member 1¹ 15 and the member 4 with its notched arm 4¹ adjustable to both sets of graduations upon the member 1¹, for securing a tight-fitting, a three-quarter tight, a half loose or loose adjustment at the neck, the plate members 6 20 and 7 laterally adjustable upon each other for bust measure, the members 8 and 27¹ adjustable relatively to each other and to the plate member 7, for laying out the arm-hole, the members 9 and 10 adjustable upon each 25 other and upon the member 8, for laying out the shoulder seam, the members 24, 23 and 18 vertically adjustable upon each other and laterally adjustable upon the member 27¹, for laying out the rear line of the coat-front, 30 the members 13, 14, 17 and 18 connected in pairs, laterally adjustable for waist and hip measures and vertically adjustable upon the members 1³, 6¹, 11, 12 and 23 for length measure, the members 15 and 21 pivoted 35 upon the members 14 and 17 and forming in connection with members 11 and 12, the means for laying out the side dart, the member 26 adjustably connecting the two lower sections of the pattern former for hip measure, and the member 22 pivoted at its upper 40 end upon the member 18 and adjustable at its lower end upon said member, for modification of the rear line of the coat front pattern, substantially as described.

45 2. In a coat front pattern former, means for securing a tight fitting, three-quarter tight, half loose or loose adjustment, said means consisting of the doubly graduated member 1¹ and the adjustable member 4 with its notched arm 4¹ adjustable to both sets of graduations upon the member 1¹, substantially as described.

50 3. An under-arm piece pattern former, comprising the vertical members 28 and 29, laterally adjustable for bust and waist measure, the member 30 vertically adjustable thereon for the under-arm length, the members 32 and 33 vertically adjustable upon the members 28 and 29 for the under-arm length 55 and laterally adjustable relatively to each other for hip measure, and the member 31 pivoted upon the member 32 and laterally adjustable relatively thereto for hip measure, substantially as described.

4. A side-gore pattern former, comprising 65 the members 37 and 34 laterally adjustable for bust measure, the members 35 and 36 superimposed upon the member 34 and laterally adjustable thereon to increase the curve thereof, the member 41 adjustable 70 upon the members 37 and 34 for the side-gore length, the members 38 and 39 vertically adjustable upon the members 37 and 34 for length measure, the member 38 being provided with arms adjustably connected to 75 members 37 and 39 admitting lateral adjustment for waist and hip measure, and the member 40 pivotally and adjustably secured to the member 38 for addition of plait to the side-gore pattern, substantially as described. 80

5. A back-piece pattern former, comprising the members 42 and 43² laterally adjustable for width of back, the member 46, 46¹ adjustable upon the member 42 for narrow chest and wide back, the member 47, 47¹ vertically adjustable upon the members 43 and 45¹ for length and allowing lateral adjustment of the member 45¹ for waist measure, and the members 48 and 49 pivotally secured upon the members 47 and 45¹ and vertically 90 adjustable thereon for length measure and laterally adjustable relatively to each other for hip measure, substantially as described.

6. A pattern former for semi-fitting, consisting of the members 50, 51, 52, 53 and 54 95 adjustably connected and adapted to increase the widths of the under-arm piece pattern former, substantially as described.

7. A pattern former for semi-fitting, consisting of the members 55, 56, 57, 58 and 59 100 adjustably connected and adapted to increase the widths of the back-piece pattern former, substantially as described.

8. A single dart pattern former, comprising the member 81 adjustably connected to 105 the graduated member 86, and the member 82 adjustably connected to the graduated member 87, the members 86 and 87 being formed with heads adjustably secured to the graduated member 85, the member 84 forming an adjustable connection between the lower ends of members 81 and 82, and the member 83 with its cross-heads 83¹ and 83², constituting a means whereby the paired members 81 and 86 may be laterally adjusted 110 relatively to the paired members 82 and 87, substantially as described.

9. A double dart pattern former, comprising the members 88 and 89, 90 and 91, 92 and 93, and 94 and 95, the members of each pair 120 being adjustably connected and the members 89 and 95 being graduated, the member 99 furnished with two independent graduated slots wherein the heads of the upper members of each pair are adjustably mounted, the members 97 and 98 adjustably connecting the lower ends of members 88 and 90 and 125 of members 92 and 94 respectively, and the

frame member 96 whereon said paired members are mounted for lateral adjustment, substantially as described.

10. A revers pattern former, comprising the member 100 furnished with the slotted head 100¹ and the slotted arm 100², the member 102 adjustably secured to said head and arm, and the slotted member 101 adjustably secured to said head, substantially as described.

11. A notch collar pattern former, comprising the members 103 and 104, and means for adjusting said members relatively to each other, said means consisting of the adjustable connected members 103¹, 104¹, 105, 106, 107 and 108, substantially as described.

12. A pattern former, comprising frames

composed of adjustably connected members for laying out the patterns for the front, the under-arm piece, the side-body, the back 20 piece, the sleeves, the collar, and the revers, with frames for semi-fittings and for single and double darts, the members of said frames being so correspondingly graduated that in laying out patterns for stock work, the members may be adjusted to the same numbered graduation as that at which the members for the bust measure are initially set, substantially as described.

MOSES DUBINSKY.
